Inventor;

D. W. Jameson.

United States Patent Office.

D. W. JAMESON, OF WARREN, OHIO.

Letters Patent No. 94,415, dated August 31, 1869.

IMPROVEMENT IN MACHINE FOR GRINDING THE CUTTERS OF MOWING-MACHINES.

The Schedule referred to in these Letters Patent and making part of the same.

To all whom it may concern:

Be it known that I, D. W. JAMESON, of Warren, in the county of Trumbull, and State of Ohio, have invented a new and useful Improvement in Machine for Grinding Harvester-Cutters; and I hereby declare the following to be a full and complete description of the same, reference being had to the accompanying drawings, making a part of this specification.

This invention consists of a device, in connection with an ordinary grindstone, whereby harvester-cutters are held to said stone while being ground, and is an improvement on the machine for grinding harvester-cutters, for which D. W. Jameson received Letters Patent, No. 83,067, dated October 13, 1868.

Said improvement consists in shortening the standards C C pivoted to the bridge-tree E.

To the top of the standards C C is an iron rod, A, fastened to them by straps, and allowed to slide back and forth, and upon which is hung the frame G, by means of slots cut in the arms B B, by which means

the frame G can be moved along the face of the stone, thereby enabling the holder to grind all the knives without moving the cutter-bar on the frame, and by which means a great deal of time and labor is saved.

By allowing the iron rod to slide, I can use a shorter rod, and by the combined sliding of frame and rod, it will be obvious that the extreme end of the cutter-bar can be brought in contact with the stone, the arm of the frame being lifted over the top of the standard C, and passing out to the end of the rod A.

What I claim as my improvement, and desire to secure by Letters Patent, is—

The rod A, fastened to the top of the standards C C, and the manner of attaching the frame G, by means of slots in the arms B B, and operating conjointly as and for the purpose substantially as set forth.

D. W. JAMESON.
